PICKER STICK FOR LOOMS

Arthur Dupres, Pawtucket, R. I.

Application December 12, 1931
Serial No. 580,717

3 Claims. (Cl. 139—146)

This invention relates to picker sticks for looms.

The primary object of this invention is to provide a picker stick of the above mentioned

5 character having certain novel and new characteristics which will endure a great amount of service in the environment in which it is used thereby eliminating the possibility of breakage and the resultant repair work causing the 10 stopping of the loom and loss of time.

A further object of this invention is to provide a picker stick for looms having a new and novel heel strap connection at the lower end thereof fastened in such a manner as to eliminate the 15 use of screws, nuts and bolts or other metallic fastening means which frequently become loose and cause considerable damage to the operation of the loom on which the picker stick is employed.

20 A still further object of this invention is to provide a lug strap support for a picker stick which may be detachably secured thereto in an adjustable fashion in order that the power applied to the shuttle may be increased or decreased without necessitating the use of tools 25 and the waste of time for making the necessary adjustments.

A still further object of this invention is to 30 provide a guard at the upper end of the picker stick to prevent the wear to which this end of the picker stick is subjected during the operation of the loom and thereby eliminating the necessary time and work required to replace a picker stick in a loom, said guard being secured to said 35 stick without weakening the latter.

A still further object of this invention is to 40 provide a picker stick for looms in which the use of nuts, bolts and screws is entirely eliminated, thereby removing the difficulty heretofore experienced in loom picker sticks due to the nuts and bolts or other fastening devices employed becoming loosened due to the shocks encountered by the picker stick when the stick strikes.

A still further object of this invention, is to 45 provide a picker stick for looms which is comparatively cheap to manufacture and which has comparatively few parts to become out of order or broken.

50 Other objects and advantages of the invention will become apparent during the course of the following description, forming a part of the specification, and in which,

Figure 1 is a vertical side elevation of the picker stick embodying this invention;

55 Figure 2 is a transverse cross-sectional view

taken on line 2—2 of Figure 1, looking in the direction of the arrows illustrating the manner in which the shuttle guard is secured to the upper end of the picker stick;

Figure 3 is a modified form of shuttle guard 60 similar to the type shown in Figure 1;

Figure 4 is a fragmentary longitudinal cross-sectional view of the picker stick showing the lug strap support;

Figure 5 is an enlarged fragmentary plan view 65 of one side of the picker stick illustrating the dove-tail slot for receiving the heel strap;

Figure 6 is a fragmentary enlarged side elevational view of the lower portion of the picker stick illustrating the dove-tail slot for receiving 70 the heel strap in detail;

Figure 7 is an elongated top elevational view of the form of heel strap particularly adapted to the dove-tail slot shown in Figures 1 and 5;

Figure 8 is a modified form of heel strap connection 75 showing the picker stick broken away and illustrating the dove-tail slot enlarged;

Figure 9 is an enlarged fragmentary edge view of the heel portion of the picker stick illustrating the grooved end portion illustrated in dotted 80 lines in Figure 8; and

Figure 10 is an elongated view of the heel strap as shown in Fig. 8.

In the drawings, wherein for the purpose of 85 illustrating the invention and wherein like reference characters will be employed to designate like parts throughout the same, the reference character 5 in Figures 1 to 6 inclusive will generally be employed to designate a picker stick

for looms having the usual shuttle engaging 90 strap 6 slidably mounted on the upper end thereof. It is proposed to form the picker stick 5

of wood or other fibrous material and secured to the upper end is a metal bar 7 secured to one edge of the picker stick by wrappings 8 of wire, 95

twine or cat gut. The metal bar 7 is preferably of cylindrical formation as shown in Figures 1, 2 and 3 and if desired, the lower end of the metal

rod 7 may have its end bent as at 9 to be received in an opening in the upper end of the 100 picker stick thereby preventing sliding movement or displacement of the metal guard from its position. In order to prevent the lateral displacement of the guard rod 7, the edge of the picker stick adjacent the upper end is grooved as at 10 so that the rod 7 may rest therein and be held in place by means of the wrapping 8

above discussed.

The lower end of the picker stick 5 is curved 110 in the usual manner as at 11 and is provided

with a vertical slot 12 extending a short distance into the ends of the picker stick and terminating in a curved portion 13. The lower end of the slots 12 communicate with a transverse cut away portion 14 clearly shown in Figure 6, and extending downwardly from the transverse cut away portion 14 is a groove as at 15, illustrated clearly in Figure 5 and shown by dotted lines in Figure 6. The slot 12 is adapted to receive one end of a heel strap as shown in Figure 1 and said heel strap is more clearly shown in Figure 7 as being provided with a section 16 secured to the main body portion 17 of the heel strap by means of rivets 18. Extending from the portion 16 toward the opposite end of the heel strap 17 is an extension 19 which is adapted to be received in the groove 15 formed in the lower portion of the slot 12, when the heel strap 17 is in place as illustrated in Figure 1, the shoulder 20 of the attached section 16 abuts against the lower transverse edge 21 of the transverse cut away portion 14 and the opposite portion of the attached section 16 extends upwardly into the slots 12 and abuts against the terminal 13 as shown in Figure 1. At the opposite end of the heel strap 17, there may be provided a slot 22 for receiving the usual coil spring whereby the picker stick will normally be moved in a clockwise direction on the pivot bolt 23.

In Figures 8, 9 and 10, there is illustrated a modified form of heel strap connection and the lower end of the picker stick 11' is provided with a dove-tail slot 12' having a lower curved edge 25 and a complementary curved section 26. The extreme lower portion of the heel is slotted as at 15' for receiving a projection 27 formed on the modified form of heel strap 17' shown in Figure 10. The heel strap is provided at one end with the usual spring receiving slot 22' while the opposite end is bent upon itself as at 16' to form an enlarged portion adapted to be received in the dove-tail slot 12' as clearly illustrated in Figure 8.

Attention is now directed to Figures 1 and 4, wherein is shown a lug strap support comprising a pair of leather straps 30 and 31 secured together at the top and bottom edges as at 32 and 33. The intermediate portions of the lug straps 30 and 31 are separable for the purpose of receiving the lug straps on the end of the picker stick operating lever (not shown). A series of pins 34 having enlarged heads 35 pass through openings in the inner strap 31 and are adapted to aline with a plurality of equally spaced openings 36 so that the lug straps formed by the sections 30 and 31 may be moved up and down relative to the picker stick 5. In practice, the lug strap passes through the space between the straps 30 and 31 and encircles the

picker stick 5 in a manner well known in the art.

It is to be understood, that any number of pins 34 having enlarged heads 35 may be secured to the section 31 of the lug strap supporter in such a manner that they aline with the holes 36 formed in one edge of the picker stick 5. It is quite obvious, that the lug strap supporter may be moved up or down relative to the picker stick in order to make the necessary adjustments for the increase or decrease of power applied to the shuttle without requiring the use of tools and lengthy manipulation for making the required adjustments.

It is to be understood, that the form of the invention herewith shown and described is to be taken as a preferred example of the same and that various changes in the shape, size and arrangement of parts may be resorted to without departing from the spirit of the invention or the scope of the subjoined claims.

I claim:

1. A picker stick for looms comprising an elongated bar, a heel section formed on the lower end of the bar and having an opening therein, a heel strap adapted to be secured to the heel portion, said heel strap including a strip of flexible material, an enlarged portion formed on one end of the heel strap, a lug formed on the heel strap and said enlarged portion and lug being adapted to be received in said heel opening.

2. A picker stick for looms comprising an elongated bar, a curved heel section formed on the lower end of the bar and having a restricted opening and communicating slot therein, a heel strap adapted to be connected to the heel section, an enlarged portion formed on one end of the heel strap adapted to be received in one restricted opening in the heel section and a lug formed on the heel strap adapted to enter the correspondingly shaped slot also formed in the heel section whereby lateral and longitudinal displacement of the heel strap relative to the heel section will be prevented.

3. A picker stick for looms comprising an elongated bar, a curved heel portion formed on the lower end thereof and having a restricted opening and communicating slot therein, a heel strap adapted to be attached to the heel portion, an enlargement formed on the end of the heel strap adapted to be received in the restricted opening formed in the curved section of the heel portion and a lug centrally formed on the heel strap adapted to be received in said slot in the curved heel section whereby the heel strap will be removably secured to the heel section of the picker stick.

ARTHUR DUPRES.
